UNITED STATES PATENT OFFICE.

HUGH L. COATS, OF WHEATON, ILLINOIS, ASSIGNEE TO FLEXIBLE STEEL LACING COMPANY, OF CHICAGO, ILLINOIS, A CORPORATION OF ILLINOIS.

HOLDER FOR WIRE BELT HOOKS.

Application filed January 7, 1927. Serial No. 159,731.

This invention relates to improvements in holder for wire belt hooks.

In the use of wire belt hooks, it is highly desirable that the same be carded or applied with uniform spacing to a holding strip or retainer in order to facilitate application of such hooks to the belt or when placing the hooks in an applying device. One of the most important considerations 10 in connection with such carded gangs of hooks is to positively insure true parallelism of the individual hooks while carried by the holder, that is, to prevent any possibility of individual hooks becoming twisted or out of line, which would interfere with the expeditious application of the hooks to the belt or insertion of them in an applying device or machine.

One of the objects of my invention is to 20 provide a very simple and inexpensive holder of the type indicated which will insure maintenance of the parallelism of the individual hooks by engaging each arm of each hook at two spaced points and, further, provide such 25 a holder which will readily permit automatic application of the hooks thereto.

Another object of my invention is to provide a holder of the type indicated which is composed of a single element and to which 30 the hooks are so attached as to practically eliminate any accidental disengagement of a hook therefrom during shipment or in the handling thereof.

Other and further objects of the invention 35 will more clearly appear from the description and claims hereinafter following.

In the drawing forming a part of this application, Figure 1 is a perspective view of my improved holder showing a number of wire belt hooks applied thereto. Figure 2 is 40 an enlarged, vertical, sectional view of the device shown in Figure 1. Figure 3 is a side elevational view of the structure as illustrated in Figure 2. Figure 4 is a plan view of the holder blank showing the openings provided therein and prior to the folding or bending thereof to final form. And 45 Figures 5, 6 and 7 are views similar to Figures 2, 3 and 4, respectively, showing a 50 slightly modified form of the holder.

In said drawing, the hooks illustrated are of well known form, each comprising a section of wire bent so as to form an apex 10, two diverging side arms 11 and 12, the free 55 ends of said arms 11 and 12 being turned in-

wardly and beveled to form prongs 13-13. As shown, one arm is longer than the other and, in carding this style of hook, the same will preferably be arranged alternately as regards the short and long arms, as clearly 60 shown. As will be understood by those skilled in the art, another well known style of hook that might be used without departure from my invention is that wherein each hook has both of its arms of the same 65 length, but alternate hooks have longer sets of arms than the others, it being customary to card such style of hooks by alternating the short arm hooks with the long arm hooks.

In carrying out my invention, I form the 70 holder of a strip of any suitable material, such as light cardboard and of such characteristics that it possesses a certain amount of inherent resiliency or springiness while, at the same time, being adapted to be folded or 75 creased to take a more or less permanent form. Such a blank strip is indicated at A and, in the flat form as shown in Figure 4, the same will be provided with two intermediate series of longitudinally spaced slots or 80 cut-outs 14 and two outer series of holes or perforations 15-15 correspondingly longitudinally spaced. In carding hooks of the style specifically disclosed in the drawing, the holes 15 of each series along one edge of 85 the strip will preferably be alternately staggered to permit of the alternate arrangement of long and short arm hooks, as shown. In the event the other style of hook above referred to is carded on my improved holder, the holes 15 would obviously be correspondingly re-located to permit alternate spacing of hooks having both arms short with hooks having both arms long.

The flat blank strip, after being perforated as above described, will be given relatively sharp creases along the dotted lines indicated at 16-16, which lines 16 substantially bi-sect the series of openings or slots 14. This sharp creasing results in rounded corners as indicated in the finished blank at 17 and best shown in Figure 2 and obviously will bring the slots 14 in said corners. The creasing or folding as aforesaid, results in the formation of two sides or arms 18-18 95 which carry the openings 15 and said arms 18 will be creased or formed so as to unite with the corners 17 by inwardly offset curved sections 19-19, thus bringing the sides or arms 18 of the holder to assume positions parallel 100 to the original slots 14. The final form of the holder is shown in Figure 1.

with the inner faces of the side arms 11 and 12 of the hooks. The central or connecting section of the holder will also preferably be curved in a direction toward the free edges 5 of the side of the holder, as indicated at 20.

With the holder constructed as described, it will be evident that there are formed more or less bead-like corners at 17, which result in giving rigidity to the holder along said 10 corners and further, the arcuate connecting section 20 will act as a spring, due to the inherent resiliency of the material, tending to force said corner sections 17 outwardly. Due to the reverse curves in the sections 19, 15 there is also a spring-like tendency of the sides 18 to spread outwardly and thus maintain close contact with the inner faces of the arms of the hooks.

In applying the hooks, the same are slipped 20 downwardly over the holder as viewed in Figure 2 or, otherwise described, by slipping the holder within the open ends of the hooks, thereby engaging the arms 11 and 12 of the hooks within the slots or cut-outs 14—14 at 25 points intermediate the ends of the arms of the hooks and approximately midway the length thereof. The prongs of the hooks obviously are entered in the openings or cut-outs 15.

30 As will be understood the size of the openings 15 and 14 are made such that they snugly fit the sections of the hooks and that for various sizes of hooks the openings or slots will be made to correspond. With the 35 parts assembled as best shown in Figures 1 and 2, it is evident that each individual hook has the two prongs thereof positively positioned by engagement with the openings 15, this engagement being at the lower extremity of the arms. Further, each individual hook is engaged and accurately spaced by the reinforcing beaded corners at points intermediate the ends of the hook arms 11 and 12 so that there is no possibility of the 40 hooks becoming tilted or displaced from parallelism. It will further be noted that the improved holder requires no extraneous means for retaining the hooks in place and also, when it is desired to insert a gang of 45 hooks in an applying machine, this may be done and a holding pin inserted within the apices of the hooks to lock the same in position without interference from the holder. In this connection, it will further be observed 50 that the holder can then be withdrawn by grasping the outer free ends of the arms of the holder, and springing them inwardly so as to disengage them from the prongs and then pull the holder out of 55 place.

The construction illustrated in Figures 5, 6 and 7 is the same as that illustrated in the other figures except that, instead of using

holes 15 for receiving and spacing the prongs of the hooks, series of slots 115 are 65 used, the latter being alternately shallow and deep to provide for the alternate arrangement of long and short arms of the hooks when this style is used as will be understood.

70 Although I have herein shown and described what I now consider the preferred manner of carrying out my invention, the same is merely illustrative and all modifications are contemplated that come within 75 the scope of the claims appended hereto.

I claim:

1. A holder for wire belt hooks of the type having an apex, diverging arms and inturned prongs at the ends of the arms, comprising; a strip of material formed to provide a base section, diverging arms, each connected to the base section by an inwardly extended offset forming a strengthening bead-like corner, said base section being slotted to provide spaced slots along said bead-like corners, and said arms being provided with correspondingly spaced cut-outs whereby the prongs of the hooks are adapted to be projected inwardly into and be spaced by said cut-outs of the strip arms and said slotted bead-like corners are adapted to project outwardly between and space said arms of the hooks intermediate the ends of the latter.

95 2. A holder for wire belt hooks of the type having an apex and diverging arms with in-turned prongs at the free ends thereof, comprising: a strip having diverging arms and a connecting section, said arms being cut 100 out to receive said prongs and arranged to lie against the inner sides of the hook arms from the prongs thereof to a point intermediate the ends of the hook arms, said strip connecting section being of greater width 105 than the distance between the inner sides of the hook arms at the point where the strip arms are united to said connecting section, said connecting section being slotted at longitudinally spaced intervals to receive 110 and space said intermediate portions of the hook arms therein.

3. A holder as described in claim 1 and wherein the material forming said strip is possessed of inherent resiliency and the arms 115 of the strip normally tend to spring outwardly.

4. A holder as described in claim 2 and wherein the strip is made of inherently resilient material and said connecting section 120 is curved toward the free edges of the strip arms.

In witness that I claim the foregoing I have hereunto subscribed my name this 3rd day of Jan. 1927.

HUGH L. COATS.
